UNITED STATES PATENT OFFICE.

ANGUS MACARTHUR, OF CHICAGO, ILLINOIS, ASSIGNOR TO THE KOPPERS COMPANY, OF PITTSBURGH, PENNSYLVANIA, A CORPORATION OF PENNSYLVANIA.

DISTRIBUTOR FOR AUTOMATIC STOKERS.

Application filed October 4, 1923. Serial No. 666,554.

The object of this invention is to provide an efficient distributing means for maintaining in boiler furnaces a well distributed fuel bed, without segregation of the fuel into piles 5 of pieces of uniform sizes, throughout the entire area of the grate. The improved distributing means of the invention is characterized by being capable of ready installation in boiler furnaces of standard type, for example, 10 boiler furnaces of the automatic-stoking type which employ a continuous and progressively moving grate; and is further characterized by great simplicity and economy of construction and installation.

15 In addition to the general objects recited above, the invention has for further objects such other improvements or advantages as may be found to obtain in the structures and devices hereinafter described or claimed.

20 In the accompanying drawings forming a part of this specification and showing for purposes of exemplification a preferred form and manner in which the invention may be embodied and practiced, but without limiting 25 the claimed invention specifically to such illustrative instance or instances:

Figure 1 is a front sectional and elevational view, in part diagrammatic, of an automatic stoking furnace of standard type equipped 30 with the improvements of the invention;

Fig. 2 is a side elevation of the front portion of such a furnace; and

Fig. 3 is an elevational sectional view taken longitudinally of the line of feed of the fuel 35 into and through the furnace.

The same characters of reference indicate the same parts in each of the several views of the drawings.

40 In the embodiment illustrated in the drawings, the invention is incorporated in a standard type of automatic stoking boiler furnace. For convenience, the present description will be confined to this illustrated embodiment of the invention; the novel features and improvements made by the invention are susceptible of other applications, for example, 45 to furnaces of other types; hence, the scope of the invention is not confined to the specific use and embodiment herein described as an 50 illustrated example.

The boiler furnace illustrated in the drawing is provided with the fire box 11 which extends through the front wall 12 of the furnace for receiving a constant supply of fuel. 55 The continuous grate 13 extends from side to

side of and through the fire box and is mounted at its front end beyond the furnace wall 12 on sprocket 14 driven by suitable gearing and power connections 15 for the purpose of advancing the upper reach of the continuous 60 grate constantly into and through the fire box.

The fuel is deposited on the grate 13 just in front of the wall 12 by a gravity feed through a hopper 16 which extends from side to side 65 of the grate. An adjustable gate 16¹ mounted in front of the fire box of the fire box opening permits regulation of the depth of the fuel bed on the grate.

In furnaces of the type just briefly described, great difficulty has been experienced in maintaining proper distribution of fuel from side to side of the grate because of the wide extent of such structures, and also because of the fact that it is common to employ pulverulent or finely divided fuels. Such fuels have a tendency, especially when moist, to agglomerate and to segregate in piles of uniform-sized pieces. These conditions of irregularity must be avoided, if 70 possible, it being well known that an irregular fuel bed, especially in furnaces of the above described type and when finely divided fuels are employed, is a great detriment to economic distribution of the heating effect. 75 Attempts have been made to avoid such irregularities but experience has proved them unsatisfactory in operation and result. For example, it has been proposed to feed the fuel into the feed hopper 16 from a swinging discharge chute. This arrangement, however, 80 involves an expensive driving equipment and does very little towards promoting equality in distribution, because of the practical impossibility of maintaining a constant volume 85 of flow of the fuel through the chute.

The distributing means of the present invention accomplishes the desired result of effecting equality in distribution of the fuel on to the grate and maintains the proper 100 mixture of sizes of the fuel from side to side of the grate by an extremely simple expedient. Extending across and supported by the sides of the upper hopper 17, which may be termed the distributing hopper, is a screw 18 105 of the ordinary screw-conveyer type. The screw 18 receives the fuel directly from the feed chute 19 and distributes it equally from side to side of the hopper 17, with the result that complete equal distribution of the fuel 110

with mixture of the different sized pieces is effected before it falls into the lower hopper 16 and on to the grate 13. This construction has been found to attain the desired result 5 of maintaining satisfactory distribution of fuel from side to side of the grate. Preferably, as shown in Fig. 1, the screw 18 is provided with both right and left hand threads which meet at the longitudinal center line 10 of the furnace, so that the distribution takes place from the center towards the sides, with the result that the amount of distribution necessary is reduced. The distributing screw 18 receives the fuel directly from the centrally mounted stationary feed chute 19 and feeds the fuel toward the opposite sides of 15 the hopper.

An intermittent drive is provided for the distributing screw 18. Secured to the constantly rotating shaft 20 of the drive mechanism is a slotted arm 21, in the slot of which projects a stud 22 carried by the lower end 20 of a connecting rod 23. The connecting rod 23 is pivoted at its upper end to an arm 24, 25 which arm is in turn pivoted on the axis of rotation of the screw 18. The arm 24 is provided with a pawl 25 which operates a ratchet 26 secured to one end of the screw. With this construction each downward thrust of the 30 connecting rod 23 causes the pawl 25 to effect a one-step movement of the ratchet 26 and screw 18. During the reverse movement of the connecting rod 23 the pawl 25 travels idly over the ratchet teeth.

35 The invention as hereinabove set forth may be variously embodied within the scope of the claims hereinafter made.

I claim:

1. The combination with a continuously 40 movable endless chain grate of a reservoir hopper extending across the entire width of said grate and mounted directly over said grate so that said grate supports a vertically descending column of fuel in said hopper as said grate takes up a portion of the fuel 45 while moving across the lower portion of said hopper; a spreader hopper above said reservoir hopper and co-extensive in length therewith and communicating throughout its 50 full length, at its lower portion, with said reservoir hopper at the upper part thereof; a distributing screw arranged in said spreader hopper and provided with both right and 55 left-hand threads respectively extending in opposite directions from a longitudinal central point in said spreader hopper to spread fuel in opposite directions in said spreader hopper from said central point and to discharge fuel from itself throughout its length; 60 a fuel delivery chute communicating with said spreader hopper at said central point for feeding fuel to said distributing screw; and driving mechanism for effecting a step-by-step movement of the distributing screw.

65 2. The combination with a stoker grate of a

reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof, and arranged to receive fuel from a source of supply; and a power-driven spreader comprising two sections arranged to move fuel from said source of supply in opposite directions in said spreader hopper and to discharge fuel from themselves to said reservoir hopper throughout their length, whereby the delivery of fuel to the upper portion of said reservoir hopper is 70 constantly uniform throughout the length thereof and the depth of reserve fuel in said reservoir hopper is maintained constant 75 throughout its entire length.

3. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof, and arranged to receive fuel from a source of supply; and a driven spreader unit arranged to move fuel from said source longitudinally in said spreader hopper and to discharge fuel from itself throughout its length to said reservoir hopper; whereby the delivery of fuel to upper portion of said reservoir hopper is constantly uniform throughout the length thereof and the depth of the reserve fuel in said reservoir hopper is maintained constant throughout its 100 entire length.

4. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof and underlying an overhanging fuel delivery chute for said reservoir hopper; and a screw in said spreader hopper for moving fuel from said chute longitudinally along said spreader hopper and adapted 115 120 125 130

- for discharge of fuel from itself throughout its length downwardly through said spreader hopper to said reservoir hopper; whereby the delivery of fuel from the chute to the upper portion of said reservoir hopper is constantly uniform throughout the length thereof and the depth of the reserve fuel in said reservoir hopper is maintained constant throughout its entire length.
5. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof; means for delivering a constant flow of fuel to the longitudinal middle of said spreader hopper; and a spreader unit comprising two screw sections in said spreader hopper on opposite sides of said means for delivering a constant flow of fuel, arranged to spread fuel in opposite directions away from said means and to discharge fuel from themselves throughout their length downwardly
- 10 through said spreader hopper to said reservoir hopper; whereby the delivery of fuel from said means to the upper part of said reservoir hopper is constantly uniform throughout the length thereof and the depth of the reserve fuel in said reservoir hopper is maintained constant throughout its entire length.
- 15 5. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof; means for delivering a constant flow of fuel to the longitudinal middle of said spreader hopper; and a spreader unit comprising two screw sections in said spreader hopper on opposite sides of said means for delivering a constant flow of fuel, arranged to spread fuel in opposite directions away from said means and to discharge fuel from themselves throughout their length downwardly
- 20 through said spreader hopper to said reservoir hopper; whereby the delivery of fuel from said means to the upper part of said reservoir hopper is constantly uniform throughout the length thereof and the depth of the reserve fuel in said reservoir hopper is maintained constant throughout its entire length.
- 25 5. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof; means for delivering a constant flow of fuel to the longitudinal middle of said spreader hopper; and a spreader unit comprising two screw sections in said spreader hopper on opposite sides of said means for delivering a constant flow of fuel, arranged to spread fuel in opposite directions away from said means and to discharge fuel from themselves throughout their length downwardly
- 30 through said spreader hopper to said reservoir hopper; whereby the delivery of fuel from said means to the upper part of said reservoir hopper is constantly uniform throughout the length thereof and the depth of the reserve fuel in said reservoir hopper is maintained constant throughout its entire length.
- 35 5. The combination with a stoker grate of a reservoir hopper extending transversely of the direction of feed by said stoker grate and mounted directly over said grate so that said grate supports a reserve column of fuel in said hopper as it takes up a portion of the fuel therein while feeding transversely across the lower portion of said reservoir hopper; a fuel spreader hopper mounted above said reservoir hopper and extending lengthwise thereof and communicating throughout its full length with said reservoir hopper at the upper part thereof; means for delivering a constant flow of fuel to the longitudinal middle of said spreader hopper; and a spreader unit comprising two screw sections in said spreader hopper on opposite sides of said means for delivering a constant flow of fuel, arranged to spread fuel in opposite directions away from said means and to discharge fuel from themselves throughout their length downwardly

In testimony whereof I have hereunto set my hand.

ANGUS MacARTHUR.
